INVENTOR

Frank M. Ashley

UNITED STATES PATENT OFFICE.

FRANK M. ASHLEY, OF NEW YORK, N. Y.

FOUNTAIN PEN.

1,419,439.

Specification of Letters Patent. Patented June 13, 1922.

Application filed January 31, 1917. Serial No. 145,581.

To all whom it may concern:

Be it known that I, FRANK M. ASHLEY, a citizen of the United States, and resident of New York city, in the county of Kings and State of New York, have invented certain new and useful Improvements in Fountain Pens, of which the following is a specification.

My invention relates to fountain pens and the object thereof is to provide simple and improved means for filling the same and for bringing a small quantity of ink from the reservoir to the pen point when the feed is dry and not feeding properly.

Referring to the drawings which form a part of this specification,

Fig. 1 is a longitudinal sectional view through the barrel, disclosing the new presser-bar in position therein;

Fig. 2 is an exterior view of same;

Fig. 3 is a plan view of my presser-bar; and

Fig. 4 is a cross sectional view through the barrel disclosing an end view of the presser-bar ring.

The improvement consists in the form of the presser-bar and the means of holding it in the barrel and also providing it with a button, which is located in an opening in the barrel, and by means of which the ink can be forced to the pen point by pressing a finger thereon.

A, indicates the barrel or casing of the pen, and B, the usual rubber sack which is connected to the pen section C, in the usual manner.

In Fig. 1, I have shown the presser-bar bent to form a projection D' which is located in the opening A' in the barrel and the top of which comes flush with the outer surface of the barrel.

The button is made with a depression at its centre, indicated by D² and any small article, such as a toothpick or pin may be used to force it downward in order to collapse the sack in filling, the depression D² which may be cone shaped, preventing the point from slipping from its position in the button and piercing the sack.

The presser-bar is formed with a ring at one end indicated by D⁴ and cut away at one side as shown at D⁷ in Fig. 4, to form a spring by means of which the bar is supported firmly in position. I prefer to form on the ring one or more projections D⁵ D⁶ which enter holes A² A² formed in the bar-

rel, which prevents the bar from shifting its position and holds it firmly under the opening A'.

By holding the presser-bar at the forward end of the barrel, the free end of the bar naturally moves downward first when the button is depressed in the act of filling the pen and therefore the closed end of the sack will be first collapsed, thus preventing any ink remaining in the sack from the previous filling being trapped and the sack ruptured, as is apt to happen when the bar is anchored at the rear end of the barrel, and also insures the complete collapsing of the sack and consequently the complete filling thereof in expanding.

I prefer to form a slight curve D⁶ in the presser-bar as the bar will bend at said curved point and sink to a lower point in the barrel when constructed in this manner, lessening the bending strain on the bar at this point due to the spring action of the curved portion and insuring a more complete collapsing of the sack adjacent the pen section.

In using the pen in case the point gets dry and is not fed freely, the first finger of the hand can be instantly placed on the button and by pressing it, the sack may be slightly pressed to cause enough ink to flow to wet the pen point, and this feature has proved very serviceable.

The button is exposed and ready for instant use at all times by the operators finger and also serves its function perfectly in the act of filling the pen.

Having described my invention, I claim as new,

A fountain pen comprising a barrel having an opening in one side thereof, a sack, a presser-bar having a projection located in said opening the top of which is disposed flush with the outer surface of the barrel, said presser bar having a ring at one end provided with a projection adapted to engage the wall of an opening formed in the barrel, said barrel having an opening to receive said projection. 95

Signed at New York city, in the county of Kings and State of New York this 8th day of November, A. D. 1916. 105

FRANK M. ASHLEY.
